HOOD LATCH UNIT

Robert L. Townsend, Sherman Oaks, Calif., assignor to
A. C. Stearns Co.

Filed Oct. 30, 1969, Ser. No. 19,857

Term of patent 14 years

Int. Cl. D8—04

U.S. Cl. D8—265

FIG. 1 is a perspective view taken from below, with spring removed for clarity of illustration, of a hood latch unit in accordance with the present invention;

FIG. 2 is a perspective view of the mounting bracket portion thereof;

FIG. 3 is a side elevational view thereof, in open position;

FIG. 4 is a front elevational view thereof, in closed position; and

FIG. 5 is a top view thereof.

The vehicle hood portion shown in broken lines is included for illustrative purposes only.

I claim:

The ornamental design for a hood latch unit, substantially as shown and described.
